Fig. 1

Fig. 2

Fig. 3

FIG. 1 is a top plan view of a dish warming stand or similar article embodying my new design.

FIG. 2 is a side elevational view of the same.

FIG. 3 is an end elevational view of the same.

The views of the stand opposite to those shown in FIGS. 2 and 3 are mirror images thereof.

The dominant features of my design reside in the portions shown in full lines.

I claim:

The ornamental design for a dish warming stand or similar article, as shown and described.
